UNITED STATES PATENT OFFICE

136,347

DESIGN FOR A PICTURE FRAME

Jack E. Schenker, Chicago, Ill.

Application July 22, 1943, Serial No. 110,729

Term of patent 7 years

To all whom it may concern:

Be it known that I, Jack E. Schenker, a citizen of the United States, residing at Chicago, in the county of Cook and State of Illinois, have invented a new, original, and ornamental Design for a Picture Frame, of which the following is a specification, reference being had to the accompanying drawing, forming part thereof.

Fig. 1 is a perspective view, showing particularly the front of my picture frame embodying my new design, and

Fig. 2 is a front elevational view of the same picture frame.

I claim:

The ornamental design for a picture frame, as shown.

JACK E. SCHENKER.
